UNITED STATES PATENT OFFICE.

ETIENNE SALOMON, OF MONTREAL, QUEBEC, CANADA, ASSIGNOR OF ONE.
HALF TO EDMOND ARMANT, OF SAME PLACE.

PUNCHING AND CUTTING MACHINE.

SPECIFICATION forming part of Letters Patent No. 272,332, dated February 13, 1883.

Application filed May 3, 1882. (No model.) Patented in England July 25, 1882, No. 3,537.

To all whom it may concern:

Be it known that I, ETIENNE SALOMON, of the city of Montreal, in the district of Montreal and Province of Quebec, in the Dominion of Canada, have invented certain new and useful Improvements in Punching and Cutting Machines; and I do hereby declare that the following is a full, clear, and exact description of the same.

This invention relates to improvements in machines for manufacturing metal washers, hinge-plates, metal checks of all kinds, and different descriptions of articles generally cut from a metal plate and requiring to be afterward punched or perforated. Its object is to perform the work of cutting and punching in one operation, to flatten out all ragged edges, and to turn out an article finished in every respect and ready for the use to which it is to be applied.

My invention includes, also, a self-feeder, which enables me to operate much more quickly than can be done with the present hand methods, besides insuring perfect accuracy in cutting and punching and avoiding all waste of material.

In the following description I shall allude only to the manufacture of washers, (which by my machine will be certain to have the hole always punched exactly in the center;) but this is only for purposes of shorter explanation, and must not be considered as confining me to such class of articles alone, as by a simple change of dies and punches I can adapt my invention to a great variety of uses, as already mentioned.

In the accompanying drawings, Figure 1 is a side elevation, partly in section, of my machine; Fig. 2, a front elevation of same; Fig. 3, a back sectional elevation taken on the line X X, Fig. 1; Fig. 4, a view showing cams for operating punches and self-feeder and driving-gears arranged in their relative positions; Fig. 5, an enlarged sectional detail view, showing die-block and punches; Fig. 6, a sectional plan, showing arrangement of shafts, &c., operating self-feeder; and Fig. 7, a detail of device for imparting motion to feed-lever.

Similar letters of reference indicate like parts

in the following description and in all the figures.

A is the frame of the machine, and B its bed-plate, made somewhat of the configuration shown. In this frame are formed suitable journals for two horizontal shafts, C and D, which carry on their front ends cams marked, respectively, E and F, (to be hereinafter more particularly described,) and on their rear ends gear-wheels G and H. These gear-wheels intermesh with a small pinion, I, mounted on a short shaft, K, (journaled in the frame,) which also carries a fly-wheel, L, and pulley l, cast integral with each other. The pinion I and fly-wheel L have holes cut in them, in which two or more pins, i i, firmly fixed to a grooved collar, M, mounted on the inner end of the shaft K, work, as will be seen clearly in Fig. 1. This mechanism forms a clutch for throwing the moving parts of the machine in and out of gear with the fly-wheel and pulley; but its particular construction is not necessary to the working of my invention, as any suitable or ordinary clutch may be used in its stead.

The collar M is formed with a suitable cam-groove, m, in which a pin, N, is thrown when it is desired to withdraw the pins i i from their bearings in the hub of the fly-wheel L, and thus stop the machine. The pin N is carried on the upper end of a skeleton pitman, N', as shown in Figs. 1 and 3, and a small roller, n, on this pitman impinges on the periphery of a pulley or cylindrical projection, H', cast in one with the gear-wheel H on its inner side, said pulley having an indentation or recess, h, formed in its rim, into which the roller n falls by the means to be described at every complete revolution of the gear H, and thus holds the pin N firmly in the cam-groove m, and as this cam-groove works round upon the pin N the pins i i are drawn out of the hub of the fly-wheel L and the working of the machine ceases. To withdraw the roller n from the recess h, a lever, O, pivoted at o to the frame, connected at one end to the pitman N', and provided at the other with a counterbalance weight, O', is raised at the counterbalance end by depressing a treadle, O², connected to the lever O by a short arm, O³, and consequently

lowering the end which is connected to the pitman N' , and releasing the roller n from the recess h and the pin N from the grooved collar M , which latter is thrown again into gear with the fly-wheel and pulley by pressure exerted on its end by one or more spring-levers, $P.P.$, pivoted to the frame, as shown in Figs. 1 and 3.

The cam E , carried by the shaft C , is for the purpose of raising and lowering the punch E' , which first cuts the washer from the strip of metal, and is shown in Figs. 1 and 4. e is a cam-groove of the configuration indicated in Fig. 4, in which works a roller, e' , mounted on the end of a stud, e^2 , adjustably secured in a slot, e^3 , formed in a slide, Q , running in guides $Q'Q'$, bolted to the front of the machine.

To the lower end of the slide Q the punch or cutter E' is secured by a set-screw, r , or other means, which will permit of its being removed and another one substituted. This punch and part of the slide Q are made hollow to allow of the center pieces cut from the washers by the lower punch, about to be described, to pass upward and out onto a chute, r' , which conveys them to a scrap-basket, as shown in Figs. 1 and 2.

The cam F , described as mounted on the front end of the shaft D , serves to raise and lower the punch R , which cuts the central hole through the washer after it has been formed and forced by the punch E' down to the bottom of the die-block R' . This punch R is secured in the upper end of a slide, S , working in guides $S'S'$. In the cam F is formed a cam-groove, f , in which works a small roller, f' , mounted on a stud, f^2 , adjustably secured in a slot, f^3 , formed in the slide S , all arranged in a manner similar to that described for the cam E . The die-block R' is carried in the frame A in any suitable manner, and is arranged to allow the punch E' to follow the washer, after it is cut, clear down to the bottom of its matrix, so that this punch may press and flatten out the washer, and at the same time hold it firmly while the punch R comes up and cuts the center hole.

Through the die R' , at the bottom of the matrix, a slot, r^2 , is formed, in which an ejector, T , slides, so that at each operation the finished washer may be expelled therefrom. This ejector is operated by a lever, T' , connected thereto and pivoted to a cross-head, T^2 , in the frame, (its pivot-pin being changed to different holes, so as to lessen or increase the throw of the ejector and adapt it for varying sizes of work,) and its upper end is provided with a small roller, t , and works in a cam-groove, C' , formed in a collar carried by and revolving with the shaft C . This device is so arranged as to be timed to act when the cams have withdrawn the punches from the die-block.

I will now describe my newly-invented devices for feeding the metal plate from which the washers are to be cut forward to the punches and die.

The gear H , mounted on shaft D , has its

outer face formed with a cam-groove, h' , in which works a small roller, h^2 , carried by a short spindle, h^3 , which slides in a curved slot, u , formed in a standard, U , bolted to the bed-plate of the machine. The spindle h^3 has also attached to it one end of a lever, U' , the opposite end of the latter being pivoted to a vertical rod, U^2 , which carries at its upper end a pawl, u' , working in a ratchet, V , mounted on a shaft, V' , extending from back to front of the machine, and suitably journaled. Toward the front, and in a line with the punches and die, this shaft V' carries a roller, V^2 , and at its extreme end is provided with a bevel-gear, v , which intermeshes with a similar gear, v' , on the end of a counter-shaft, V^3 , extending across the front of the machine through a similar pair of gears, $v^2 v'$, which serves to rotate another roller, V^4 , at the opposite side. Immediately above each of these rollers $V^2 V^4$ are placed other rollers, $V^5 V^6$, of like nature, carried by suitable brackets, all as shown in Fig. 2 and 6, and between these double rollers the strip or plate of metal from which the washers, &c., are cut is placed, and they serve to feed the same forward to the punches and die at regular intervals with the other operations. The length of feed is regulated by sliding a block, W , (shown particularly in Fig. 7,) forward or backward in a slot, w , formed in the lever U' , a short bolt, w' , also working along a straight slot, w^2 , in the standard U , the parts being fitted loosely enough, (but firmly,) so as to allow the spindle h^3 to at all times follow the curved slot u , although the radius from the bolt w' may be changed. It will be seen that as this radius is altered the number of teeth on the ratchet V embraced by the pawl u' is increased or lessened, and accordingly the length of feed of the material to be operated upon can be varied in this manner to suit different classes of work.

When my machine is to be used for cutting washers, &c., from scrap or metal plates of sizes and shapes which will not permit of my self-feeding attachment being worked to advantage, the same may be removed and the feeding be done by hand.

The operation of the machine may be described as follows: Power is communicated to the pulley l through a belt in the usual manner, and the pinion I and grooved collar M being in gear, as described, rotary motion is imparted to the gears G and H , which in turn revolve the shafts C and D and cams E and F . These cams are arranged in relation to the gears as shown in Fig. 4, the cam E being there indicated as having revolved sufficiently to bring its longest surface (marked 1) to bear on the roller e' , affixed to the slide Q , so as to throw the punch E' (which performs the first operation) to the full extent of its stroke, or down to the bottom of the die-block R' , as shown in Fig. 1. The punch R is then midway in its upward stroke by reason of the roller f' , (through which the slide S and punch R

are operated,) having been raised by the middle surface, 3, of the cam F. By the continued revolution of the gears this cam presents its longest point 4 to the roller f', and thus forces the punch R up through the washer (thus cutting the central hole) and into the hollow formed in the punch E', driving the waste piece before it. These waste pieces are forced out through a continuation of the hollow space in the slide Q one by one, and roll down the chute r', as already described. The cams continue to revolve, and when their shortest surfaces (marked 2 and 5) bear on the respective rollers the punches are withdrawn, and the cam-groove C' operates on the end of the lever T' and forces the ejector T into the slot r² at the bottom of the die-block R', and expels the finished washer. Simultaneously with the action of this ejector the cam-groove h' on the outer side of the gear H presents its shortest side, 6, to the roller h², and raises the same and the inner end of the lever U', and consequently draws downward the vertical lever U², pivoted to the outer end of U', thus causing the pawl u' to rotate the ratchet V, and, through the shafts V' V³ and their miter-gears, also revolves the feed-rollers V² V⁴, which thus feed the metal plate forward the required distance to allow another washer to be cut by the next strokes of the punches. Immediately after one washer is completed and expelled from the die-block and the plate again fed forward the machine stops by reason of the roller n falling into the recess h on the pulley H', and the consequent holding of the pin N in the cam-groove m, which withdraws the pins i i from the hub of the fly-wheel and driving-pulley, as already described. It is therefore necessary to depress the treadle O² to release the roller n and withdraw the pin N from the cam-groove, so that the spring-levers P may again throw the pins i i into the holes in the fly-wheel hub, and the operation of cutting the next washer proceeds. When, however, it is desired to proceed with the operation continuously, the treadle O² may be kept always depressed, or the action of the counter-balance O' overcome or prevented by any other suitable means—such as a locking-stop, &c. The roller n will then ride over the recess h, and a continuous operation is insured.

Should it be so desired, the gear H may be made plain on its outer surface and a separate cam be mounted on the shaft D for the roller h² to work in; but I prefer the arrangement shown and described herein.

In view of the state of the art, and partly of English patent to Hay, No. 1,223 of 1880, I do not wish to claim, broadly, the use of a descending punch for cutting the washer from a plate and an ascending punch for making the central hole, said punches being operated through slides worked by horizontal geared shafts, as I am aware that washers have been made by such mechanism; but in none of these machines has it been possible to so time the op-

erations as to enable the upper punch to cut the washer and then press it out flat on the bottom of the die-block before the lower punch ascends to cut the central hole. This serious deficiency has been caused by the use of links operated upon by the horizontal shafts to raise and lower the slides carrying the punches. Again, in these machines no means for adjusting or regulating the throw of the punches have been used, and experience has proved that unless a device for this purpose is provided, as the punches wear or are ground down in sharpening, the work of cutting and punching cannot be satisfactorily performed without the insertion of new cutting-tools. My specific arrangement of cams and devices for adjusting the throw of punches effectually overcomes all these objections.

Having thus described the construction and operation of my invention, I beg to state that what I claim, and desire to secure by Letters Patent, is as follows:

1. In a machine for cutting and punching washers and like articles, the combination of the cams E and F, of substantially the configuration shown, and mounted on shafts C and D, rotated through pinion I and gears G H, with rollers e' f', adjusting-screws e² e³ f² f³, slides Q and S, and punches E' and R, all arranged and operating substantially in the manner and for the purpose specified.

2. In punching and cutting machines, and in combination with the punches and the die-block R', having the recess r², the mechanism for operating said punches in the manner set forth—that is to say, forcing the upper punch downward after it has cut out the washer, carrying the washer with it and firmly pressing it on the bottom of the recess r², and holding it there until after the lower punch shall have ascended and punched a hole therein.

3. In a machine for cutting and punching washers and other like articles, the combination, with the die-block R', having slot r², of the ejector T, automatically operated by pivoted lever T', receiving motion from a cam on the shaft C, which operates one of the punches so as to automatically expel the finished washer without stopping the machine, substantially as described.

4. The combination, with the pulley H', cast in one with the gear H, and having recess h, of the roller n, carried by skeleton pitman N', pin N, grooved collar M, and a clutch for engaging with the hub of the driving-pulley, and a system of levers for withdrawing said roller from said recess, and means for returning the clutch, substantially as and for the purpose set forth.

5. The herein-described self-feeding mechanism, consisting essentially of the lever U', operated by roller h² and a cam-groove on the gear H, vertical feed-lever U², pawl u', ratchet V, shafts V' V³, geared together, and the rollers V² V⁴ V⁵ V⁶, arranged substantially as described, for the purpose specified.

6. The herein-described means for adjusting the length of feed, consisting of the block W, adjustably secured in slot w in lever U', said lever having spindle h^3 at its end, working in curved slot u in the standard U, and the pivot of said block W, working also in a straight slot, u^2 , in the said standard, the parts being fitted loosely to allow spindle h^3 to follow curved slot u at each change of radius, substantially as specified.
- 5 ETIENNE SALOMON.
